UNITED STATES PATENT OFFICE

AVROM BAYAR GOODMAN, OF NEW YORK, N. Y., ASSIGNOR TO FICKS REED COMPANY, OF CINCINNATI, OHIO, A CORPORATION OF OHIO

DESIGN FOR A CHAIR

Application filed August 28, 1930. Serial No. 36,812. Term of patent 3½ years.

To all whom it may concern:

Be it known that I, AVROM BAYAR GOODMAN, a citizen of the United States of America, and a resident of New York, in the county of New York and State of New York, have invented a new, original, and ornamental Design for a Chair, of which the following is a specification, reference being made to the accompanying drawing, forming a part thereof.

The figure is a perspective view of a chair showing my new design.

I claim:

The ornamental design for a chair, as shown.

AVROM BAYAR GOODMAN.
